FURNACE PALLETS

Frank J. Boron, Elyria, Ohio, assignor to American Brake Shoe Company, New York, N.Y., a corporation of Delaware

Filed Sept. 30, 1957, Ser. No. 686,939

3 Claims. (Cl. 266—21)

This invention relates to a pallet of a kind for moving ore material through a furnace area. 15

It is common practice in processing ore material such as iron or the like to sinter the material in a furnace. Thus, ore material in a relatively finely divided state is moved through the furnace so as to be fired therein, and during firing the material is sintered so as to be agglomerated into larger size cakes. In the instance of iron ore, the large cakes are the source of iron ore for blast furnace smelting.

The foregoing treatment of the ore material is usually accomplished by having resort to grates in the form of large, heavy cast iron sections. The grates in turn are usually supported on a rigid framework of cast iron, usually a one-piece casting, and the assembled grate and support are used as a pallet or conveyor. To this end, the framework or base for the grates is sometimes provided with rollers, and a conveyor path or track is afforded for the rollers enabling the assembly to move into, through and out of the furnace. The conveyor path is sometimes of endless form, being reversed at the opposite ends thereof, so that after passing through the furnace the grates and support therefor are inverted.

It has been found, however, that cracking and warpage of the grates is becoming increasingly frequent, and in many instances the grates are actually burned out, especially as it has been found necessary in recent years to use higher and higher temperatures in the furnaces. This, coupled with the relatively heavy nature of the grates and the support therefor, tending to introduce serious maintenance considerations, have pointed in recent years to the need for substantial improvements in this type of furnace equipment, especially since it is recognized that in future years temperatures in the furnaces are going to be even higher.

In view of the foregoing, it is an object of the present invention to replace grates as heretofore used for the above purpose with a flexible open-mesh chain-type hearth consisting of articulated links. Thus, instead of a heavy cast iron grate having little resistance to thermal shock and stressing, the present invention utilizes a multitude of individual links each adapted to expand and contract individually whereby the possibility of warpage and cracking is reduced to a minimum. Additionally, the links can be cast of a heat resistant alloy whereby the life thereof is greatly enhanced and prolonged in comparison to the conventional grates. The links are spaced one from the other so that a significant area of the pallet, from ten percent to twenty percent is open, enabling contraction and expansion to occur freely and enabling the hot atmosphere in the furnace to be readily accessible to the ore material on the hearth. In the event that one particular link should perchance be thermally damaged, it is merely necessary to replace that particular link. This can be conveniently accomplished as will be explained.

The rigid framework for supporting grates as mentioned above is of course subjected to the same sort of

thermal stressing in an ore treating furnace as the grates, and identical problems are encountered. Moreover, the combined weight of the grates and the framework necessitates the use of substantial and expensive elements in 5 the conveyor flight used to convey the assembly into, through and out of the furnace, especially where the conveyor flight is reversed on itself. Accordingly, another object of the present invention is to utilize with the above mentioned chain-type hearth a support therefor consisting primarily of a plurality of light-weight centrifugally cast tubes. These have substantially less weight than the heretofore used rigid framework of cast iron, and additionally can be cast of a heat resistant alloy. The ends of the flexible chain-type hearth can be joined to the tubes whereby the intermediate area of the hearth is loose and flexible. Therefore, in those instances where a reversing conveyor path is used, the intermediate area of the pallet is in effect jostled and flexed as it passes about the reversing end of the conveyor flight after leaving the furnace, and this will have the effect of cleaning the hearth by shaking residual ore material therefrom. Additionally, the tubular construction of the support for the pallet achieves high strength with low weight, and the capability of casting the tubes of heat resistant alloy imparts long life thereto.

Other and further objects of the present invention will be apparent from the following description and claims and are illustrated in the accompanying drawings which, by way of illustration, show a preferred embodiment of the present invention and the principle thereof and what is now considered to be the best mode contemplated for applying that principle. Other embodiments of the invention embodying the same or equivalent principle may be used and structural changes may be made as desired by those skilled in the art without departing from the present invention and the purview of the appended claims.

In the drawings:

Fig. 1 is a plan view of the pallet of the present invention, a fragment only of the hearth being shown, and the intermediate tube being shown partly in section;

Fig. 2 is an end view of the pallet shown in Fig. 1, being partly in elevation and partly in section, and taken substantially on the lines 2—2 of Fig. 1;

Fig. 3 is a sectional view of the pallet taken substantially on the line 3—3 of Fig. 1;

Fig. 4 is a top plan view of one of the numerous links of the hearth;

Fig. 5 is a side elevation of the link shown in Fig. 4;

Fig. 6 is a top plan view of one of the side links for the hearth;

Fig. 7 is a side elevation of the link shown in Fig. 6;

Fig. 8 is a partial plan view of an enlarged scale of a portion of the hearth;

Fig. 9 is a perspective view of an intermediate link; and

Figs. 10 and 11 are views of a repair link, reduced in scale.

The present invention in one form is illustrated in Fig. 1 as embodied in a pallet 20 which is adapted to be moved into and through a furnace. The pallet 20 includes a primary or base support 21 the details of which will be described hereinafter, and supported by the base 21 is a flexible, chain-type hearth 25, a fragment of which is illustrated on an enlarged scale in Fig. 8. The hearth 25 is of general rectangular extent, and the front and rear ends thereof are secured, in a manner to be explained, to the front and rear tubes 26 and 27 included in the base support. The hearth 25 presents a substantially planar upper surface as can be seen in Fig. 2, and the upper surface thus afforded is adapted to support for firing in the furnace particles of iron ore

or the like to be subjected to the hot atmosphere of the furnace.

In accordance with the present invention, the base support 21 is of relatively light weight construction in comparison to what has heretofore been afforded in equipment of this general order. As mentioned above, the support 21 includes at least a front and rear tube 26 and 27, and in order that some appreciation may be had of the general dimensions of the structure here involved it may be pointed out that the tubes 26 and 27 in one embodiment of the invention are approximately five and one-half feet long with an outside diameter of approximately five and one-half inches. In the present instance, the base member 21 also includes an intermediate tube 30 which is adapted primarily to prevent sagging of the internal portion of the hearth 25. The tubes 26, 27 and 30 are cast centrifugally of a heat resistant alloy so as to impart to the base member 21 a relatively long thermal life, and the hollow nature of the tubes achieves substantial strength with low weight.

The arrangement of supporting tubes of the base member 21 which supports the hearth 25 is one of general rectangular extent, and in achieving this configuration the ends of the tubes are connected to side plates as will be described, and the side plates in turn, in one embodiment of the invention, carry rollers so that the pallet unit 20 can be guided into, through, and out of the furnace along a track. Thus, as shown in Figs. 1 and 2, relatively thick, sturdy left and right hand side plates 35 and 36 are afforded in the form of one-piece castings. The side plates 35 and 36 have flat inner faces 37, and left and right hand mounting plates 39 and 40 are disposed against the flat inner faces of the side plates 35 and 36. A plurality of mounting studs as 41 are extended through bored openings in the side plates and have threaded inner ends 42, Fig. 2, which are threaded into corresponding tapped openings formed in the outer faces of the mounting plates 39 and 40. The studs 41 have threaded outer ends 43 which project outwardly of the outer sides of the end plates 35 and 36, and nuts 45 are threaded thereon to tightly clamp the mounting plates to the side plates so as to become, in effect, a part thereof.

The mounting plates 39 and 40 are cast members and are cast with a plurality of hollow bosses 50 corresponding in number and spacing to the tubes. Thus, each of the mounting plates in the present instance includes three bosses 50. The ends of the tubes 26, 27 and 30 are telescoped onto the bosses 50 so that the ends of the tubes abut shoulders 50S, Fig. 2, on the mounting plates defining the base of each boss 50. The opposite ends of each of the tubes 26, 27 and 30 are each provided with an annular chamfer, and this chamfer is filled with a butt weld W-1, Fig. 1, fused to the shoulders 50S, thereby rigidly connecting the tubes to the mounting plates included as parts of the side plates. Additionally, each tube at each end thereof is formed with upper and lower openings, and these openings, as shown in Fig. 2, are filled with plug welds W-2 fused at corresponding points to the bosses 50.

As shown in Fig. 2, each side plate 35 and 36 is cast with a pair of outwardly projecting bearing blocks 60. An opening 61 is formed in each bearing block 60, and a bearing bushing 62 is pressed therein for rotatably supporting a journal 65 of a flanged wheel or roller 66, there thus being four such wheels on the assembly.

Each of the side plates 35 and 36 is additionally formed with a vertical flange 70 which is disposed in a plane spaced outwardly of the plane of the corresponding flat inner face 37 of the related side plate. A lock pin 71 is mounted in each flange 70 substantially at the medial portion thereof. Such lock pin extends inwardly so as to be spaced above the opposite end portion of the intermediate tube 30, and serves to limit excessive flexing of the intermediate portion of the flexible hearth 25, especial-

ly when the assembly is inverted, as will be appreciated from the description to follow.

The hearth 25 consists primarily of a multitude of individual links 75, Figs. 1 and 4, each cast as a one-piece part of heat resistant alloy. Referring to Figs. 4, 5 and 9, each link 75 includes a top plate 76 of a general rectangular configuration having a flat upper surface. Each link 75 additionally is formed with a pair of generally U-shaped end collars 77 and 78 which are of reduced dimension in comparison to the lateral width of the top plate 76. As shown in Figs. 5 and 9, the end collars 77 and 78 afford end openings 79 and 80, and the lower ends of the collars 77 and 78 are joined by a bottom plate 82 having the same width as the collars. The links 75 are reinforced by a relatively narrow vertically disposed web portion 85 which is medially located between and joins the opposed faces of the plates 76 and 82. The ends of the web 85 are arcuate as will be observed in Fig. 5 and cooperate with the end collars to define the openings 79 and 80. As shown in Fig. 9, outwardly projecting lugs as 86 are formed on the edges of the bottom plate 82 of the links 75 so as to be coplanar therewith. The ends of the lugs 86, as shown in Fig. 4, are aligned with the outer edges of the top plate 76.

All of the links 75 used for the hearth 25 are of identical construction, and as shown in Figs. 1 and 8 are adapted to be arranged in a side by side relation in transverse or lateral rows between the side plates of the pallet with the end collars of the links in each row aligned to place the openings defined by the end collars in registry. The dimensions of the links is such that when so aligned in rows, the adjacent end collars as 77 of an adjacent pair of links as L-1 and L-2, Fig. 8, in a particular row are spaced apart, this being primarily due to the narrowed dimensions of the end collars in comparison to the top plates 76. The spacing between the end collars thus afforded enables the opposite end collar 78 of a link L-3 in the next adjacent row of links to be disposed therein so that the opening defined by the end collar 78, Fig. 8, is in registry with the openings afforded by the two spaced end collars 77, Fig. 8.

The ends of the links in adjacent intermediate rows of links that are thus interfitting in the manner shown in Fig. 8 are articulated, and this is conveniently accomplished by pivotally associating the interfitting ends of the links as by elongated rods or pins 90, Fig. 1, passed through the registered openings in the interfitting ends of the links. The two end rows of links are articulated to the support 21 in a manner to be explained.

The dimensions of the support 21 of course determined in relation to the transverse span of the chain-type hearth, or alternatively, for a given furnace installation having a pre-determined track span, the links are accordingly dimensioned in relation to the track span. In any event, it is advantageous to have the links in the various rows spaced one from the other to enable the hot atmosphere in the furnace rising upwardly between the spaced support tubes 26, 27, and 30 to gain access to material to be fired that is carried on the substantially planar surface of the hearth afforded by the top plates 76 of the links 75. Accordingly, the top plates 76 and the lugs 86 of the links 75 are so dimensioned that when the collars 77 and 78 are in interfitting abutted relation as shown in Fig. 8, spaces S are established between the adjacent side edges of the top plates of adjacent links in a row. In like manner, the ends of adjacent lugs 86 are spaced the same distance S at the underside of the links, and since the bottom plates 82 are of reduced width in comparison to the top plates 76 there will be quite extensive spacing between adjacent edges of adjacent bottom plates in the rows of links. In this manner, the material to be fired on the hearth is extensively exposed to the furnace atmosphere. In this connection, it may be pointed out that I have found that the spacings established in the

above manner at the upper surface of the hearth is advantageously about seventeen percent, but this can be conveniently varied depending on circumstances between ten and twenty percent.

It will be recognized that the links in effect zigzag in a front to rear direction as viewed in Fig. 1 due to the particular manner of interfitting the links. Therefore, in order to, in effect, establish a straight edge at the two side extremities of the hearth for purposes of properly and neatly relating the hearth to its support, I provide side links 100, Figs. 1, 6 and 7 which are used in alternative rows of links. As can be seen in Fig. 1, five rows of links are used in the hearth of the particular embodiment illustrated, and therefore four such side links 100 will be used, two each for the ends of the second and fourth rows of links. The side links can be viewed as a union of one link 75 and half of another link 75. Thus, each side link 100 is provided with inner end collars 77A and 77B and a top plate 76A joined integrally thereto. Each side link 100 has what constitutes an inside section and an outside section. The outside section will be adjacent the side plate of the base support 21, and referring to Fig. 6 this outside section is afforded by forming the top plate 76A with an outside extension 76AE, and the extension 76AE is in turn formed with a pair of end collars 77AE and 77BE which are of half width in comparison to the end collars 77 and 78. The spacing between adjacent end collars as 77A and 77AE corresponds to the width of an end collar of one of the links 75. Thus, as shown in Fig. 8, the end collar 78 of an ordinary link L-4 is disposed between the end collars 77A and 77AE of the side link 100, and the relation is such that the same sort of spacing as S described above is established.

Referring to Figs. 1 and 3, a pair of generally L-shaped retainer bars 100 and 101 having vertical flanges 105 and 106 are welded at the lower edges of the flanges to the end tubes 26 and 27 of the hearth support. The horizontal flanges 107 and 108 of the retainer bars are spaced above the upper surfaces of the tubes 26 and 27 and extend inwardly of the supporting area. The retainer bars are identical in construction, and the horizontal flange in each instance is formed with a plurality of spaced apart horizontal teeth 110, Fig. 1. The spacing between the teeth 110 corresponds to the width of the end collars 77 and 78 of the links 75, whereby the end collars of the links 75 in the two end rows of links, Fig. 1, are adapted to be fitted into the spaces between the teeth 110 of the retainer bars. As shown in Fig. 3, the teeth 110 have depending lips 111 formed with beveled lower ends which are welded to points on the upper surfaces of the tubes 26 and 27.

It was mentioned above that the rods 90 serve to articulate the several rows of links comprising the hearth 25, and as shown in Fig. 2, the rods 90 are accurately dimensioned so that the ends thereof abut shoulders 120 formed on the side plates 35 and 36 between the flanges 70 and the mounting faces 37. When the hearth 25 is laid in place, the bottom portions of the links 25 repose on upper surfaces of the tubes of the support, and the rods 90 at ends thereof are held in place by the shoulders 120 against endwise displacement.

The hearth 25 is articulated to the retainer bars 100 and 101 by means of a pair of end rods 125, Figs. 1 and 3. The rods 125 are longer than the rods 90, and apertures are bored through the flanges 70 and shoulders 120 of the side plates 35 and 36, these apertures being in alignment with the openings in the end collars of the links 75 which are positioned between the retainer teeth 110 of the retainer bars. Thus, the rods 125 are disposed between the vertical flanges and the lips 111 of the retainer bars as shown in Fig. 3. The ends of the rods 125 extend outwardly of the outer faces of the flanges 70 of the side plates as shown in Fig. 2 and are retained against displacement by washers and cotter pins as shown.

Hence, it will be seen that while the rods 90 are loose,

in a manner of speaking, the rods 125 are fixed and serve in cooperation with the teeth 110 of the retainer bars to hold the hearth to its support. By having the rods 90 loose, the hearth 25 is able to flex or shake, and hence when the assembly is inverted in those instances where the assembly is used in connection with an endless conveyor track, flexibility of the hearth enables the hearth to be self-cleaning. The lock pins 71 prevent any undue sagging at the time of inversion, and the rods 90 will not over-ride the shoulders 120 to such an extent as to cause a link to be lost.

In the event that perchance a link as 75 should be burned through, the hearth can be easily repaired by having resort to a repair link 75R, Figs. 10 and 11. The repair links 75R are exact duplicates of the links 75 but are severed or split down the center of the end collars and the web 85 as by a band saw to afford upper and lower halves 75U and 75L, Fig. 11, having split end collars. The lower plate 82 of the repair link 75R is formed with a counter-sunk opening 130, Fig. 10, for the head of the bolt B, Fig. 11. Aligned opening 131 and 132 are formed in the two half webs 85A and 85B which are produced as a result of severing a link 75, and the bolt B is adapted to be positioned in the openings 131 and 132 with the threaded end thereof projecting at the top plate of the repair link for reception of a nut N.

When a repair link is to be used, the two halves thereof will be assembled complementally in the void space of the hearth with the split end collars thereof embracing the portions of the two rods 90 that happen to have been exposed by the burned link to be replaced. The bolt B is then inserted in place, and the nut N tightened to draw the two halves of the repair link together.

It was mentioned that the relative width of the top plate and the end collars of a link 75 is what accounts for the spaces S which render the planar surface afforded by the top plates of the assembled link discontinuous at regular spaced intervals to a predetermined percentage. That this discontinuous or space area, as distinguished from the solid surface area of the top plates, is readily variable for different circumstances can be seen from the following analysis of the way in which each link is dimensioned. Thus, referring to Fig. 4, the open end collars 77 and 78 of the link each have an identical width W. The top plate 76 is wider than each collar and has two projecting side portions each of width $\frac{1}{2}W-X$. The combined width of the two side projections of the top plate, that is, $W-2X$, is less than the width W of either end collar. Hence, when three links as L-1, L-2, and L-3, Fig. 8, are assembled with the fore collar 78 of the link L-3 in one row of links interfitting between and engaged with the two spaced aft collars 77 of the links L-1 and L-2 in the next row of links, the resultant space S between the side edges of the top plates of the links L-2 and L-3 will be equal to 2X. Accordingly, by varying the value of X, the dimension of S will be varied proportionally.

It will be seen from the foregoing that the furnace pallet of the present invention is one having a strong, lightweight support of open frame-work comprising spaced centrifugal cast tubes that are conveniently joined at their outer ends to afford a support of general rectangular extent. The hearth for the pallet is flexible in nature and consists of rows of articulated links of heat-resistant alloy such as chrome-nickel steel. The two end rows of links are fastened to the outermost two tubes of the support in an articulated fashion. The ordinary links in the several rows are generally cruciform in outline and have top plates which when assembled afford a planar surface for supporting the material to be fired. This planar surface is, however, discontinuous and open at regular spaced intervals, as by interrelating the dimensions of the top plates and the end collars in the manner described. This enables the heat of the furnace rising upwardly between the spaced tubes of the sup-

port to gain access to the material carried by the hearth to be fired in the furnace. The tubes can be cast of a similar heat-resistant alloy, and hence both the tubes and the links are capable of withstanding severe thermal stressing for prolonged periods of time without warping or burning out. In the event that a particular link should be burned out, this is easily replaced as explained. In this connection, a particular advantage of the present pallet is the fact that resort can be had to alloys of considerable less density than the heretofore used cast iron constructions.

Hence, while I have illustrated and described a preferred embodiment of my invention, it is to be understood that this is capable of variation and modification, and I therefore do not wish to be limited to the precise details set forth, but desire to avail myself of such changes and alterations as fall within the purview of the following claims.

I claim:

1. In a furnace pallet for conveying ore material and the like through a furnace to be fired, a substantially rigid base support of generally rectangular extent including a set of spaced tubes cast centrifugally from a low density heat resistant alloy, side plates connected to the ends of the tubes, rollers on the side plates, retainer bars secured to the end tubes in said set and each including spaced teeth, and a flexible chain-type hearth secured at the ends thereof to said end tubes, said hearth at least in the area inwardly of the side plates consisting primarily of identical individual cruciform links cast from a low density heat resistant alloy and each comprising a top plate and a pair of end collars, the top plates of said links being substantially coplanar in the assembly and the end collars of the links being aligned transversely in rows and each of less width than the related top plate, transverse rods passed through the aligned end collars thereby articulating the ends of the links and imparting flexibility to the hearth as a unit, the end collars and top plates of the links being configured to afford spacing between the side edges of the top plates of the links in the respective rows thereby enabling the furnace atmosphere rising between the tubes of the base support to gain access to material on the hearth to be fired, the portion of the hearth between said pair of tubes being loose, retainer pins extending inwardly from the sides of the pallet to overlie marginal portions of the hearth and prevent undue flexing thereof, and the link collars at the extreme ends of the hearth being interfitting with and connected between the teeth of said retainer bars.

2. In a furnace pallet for conveying ore material and the like through a furnace to be fired, a base support comprising a plurality of spaced tubes including two end tubes, and a flexible chain-type hearth, said hearth consisting primarily of transverse rows of identical individual cruciform links each comprising a top plate and a pair of end collars of reduced dimension in comparison to

5 the width of said plate, said end collars having openings therein, the top plates of said links being substantially coplanar and the end collars of the links in each row being aligned transversely and spaced transversely one from the other in one row with the collars of the links in the next row disposed in such spaces to have the openings in the collars thereof aligned with the openings in the collars in said first row of links, transverse rods passed through the aligned openings of the end collars thereby articulating the ends of the links and imparting flexibility to the hearth as a unit, the collars and top plates of the links being configured to afford spacing between the sides of the link top plates enabling the furnace atmosphere rising between the tubes of the base support to gain access to material on the hearth to be fired, a toothed retainer bar on each end tube, and the end collars of the two end rows of links being articulated to said retainer bars, said hearth being flexible between said retainer bars.

10 15 20 25 30 35 40 45 50 55 50 55

3. In a furnace pallet for conveying ore material and the like through a furnace to be fired, a base support comprising a plurality of spaced tubes including two end tubes, and a flexible chain-type hearth, said hearth consisting primarily of transverse rows of identical individual cruciform links each comprising a top plate and a pair of end collars of reduced dimension in comparison to the width of said plate, said end collars having openings therein, the top plates of said links being substantially coplanar and the end collars of the links in each row being aligned transversely and spaced transversely one from the other in one row with the collars of the links in the next row disposed in such spaces to have the openings in the collars thereof aligned with the openings in the collars in said first row of links, transverse rods passed through the aligned openings of the end collars thereby articulating the ends of the links and imparting flexibility to the hearth as a unit, the collars and top plates of the links being configured to afford spacing between the sides of the link top plates enabling the furnace atmosphere rising between the tubes of the base support to gain access to material on the hearth to be fired, retainer means on each end tube, and the end collars of the two end rows of links being articulated to said retainer means, said hearth being flexible between said retainer means.
